UNITED STATES PATENT OFFICE.

CHRISTOPHER EISENHARDT, OF PHILADELPHIA, PENNSYLVANIA, ASSIGNOR
TO HENRY DISSTON & SONS, OF PENNSYLVANIA.

BUCKSAW-FRAME.

SPECIFICATION forming part of Letters Patent No. 394,477, dated December 11, 1888.

Application filed August 25, 1888. Serial No. 283,742. (No model.)

To all whom it may concern:

Be it known that I, CHRISTOPHER EISENHARDT, a citizen of the United States, and a resident of Philadelphia, Pennsylvania, have invented certain Improvements in Bucksaw-Frames, of which the following is a specification.

The object of my invention is to provide an effective brace for the end bars of a bucksaw-frame, and this object I attain in the manner hereinafter set forth, reference being had to the accompanying drawing, which represents, partly in section and partly in side view, a bucksaw with brace constructed in accordance with my invention.

A B are the opposite end bars of the bucksaw-frame; D, the saw-blade securely connected at its opposite ends to said bars; and F, the usual tension-rod, whereby the upper ends of the bars are connected.

The brace consists of an arched bar, G, the opposite ends of which form tenons a, for adaptation to mortises b in the bars A B, and above this arched brace-bar is a supplementary brace-bar, H, the central portion of which is arched to correspond with the arch of the central portion of the bar G, and is securely bolted or riveted to said central portion of the bar. The opposite ends of the supplementary brace-bar H, however, are bent upward, or reversely curved in respect to the arched central portion of the same, and these opposite ends likewise form tenons a', adapted to mor-

tises b', formed in the bars A B some distance above the mortises b, which receive the tenons of the bar G.

I have found that by imparting an arched form to the central portion of the supplementary brace-bar, H, and upwardly curving or bending the outer ends of the same in the manner described I provide an effective and extremely rigid brace for the bars A B, and thus insure the proper stretching of the saw-blade by means of the tension-rod F.

Having thus described my invention, I claim—

The combination of the opposite end bars, blade, and tension-rod of a bucksaw with a brace consisting of an arched main bar and a supplementary bar located above the same and secured thereto, the central portion of said supplementary brace-bar being arched to correspond with the main bar, but the opposite ends of the supplementary brace-bar being upwardly curved or bent, and the ends of both brace-bars being adapted to seats in the end bars of the frame, all substantially as specified.

In testimony whereof I have signed my name to this specification in the presence of two subscribing witnesses.

CHRISTOPHER EISENHARDT.

Witnesses:

EDWARD M. RILEY,
HARRY SMITH.

It is hereby certified that the word *Incorporated* should have been added to the name of the assignee in Letters Patent No. 394,477, granted December 11, 1888, upon the application of Christopher Eisenhardt, for an improvement in "Bucksaw Frames," making said name to read *Henry Disston & Sons, Incorporated*, and that the said Letters Patent should be read with this correction therein that the same may conform to the record of the case in the Patent Office.

Signed, countersigned, and sealed this 18th day of December, A. D. 1888,

[SEAL.]

H. L. MULDROW,

First Assistant Secretary of the Interior.

Countersigned:

BENTON J. HALL,

Commissioner of Patents.
